FUSE TESTER CASING

Joe L. Alexander, Puryear, Tenn., assignor to
Guy L. Gray, Paducah, Ky.

Filed July 24, 1961, Ser. No. 66,026

Term of patent 14 years

(Cl. D26—1)

FIG. 1.

FIG. 2.

FIG. 3.

FIG. 4.

FIG. 5.

FIGURE 1 is a perspective view of a fuse tester casing, embodying my new design;

FIGURE 2 is a top plan view;

FIGURE 3 is a front elevational view;

FIGURE 4 is an end elevational view; and

FIGURE 5 is a rear elevational view thereof. The end not shown is substantially plain and unornamented.

The broken line showing of a battery is for illustrative purposes only.

I claim:

The ornamental design for a fuse tester casing, as shown and described.
